CLAIM

The ornamental design for a tub for bathing, as shown and described.

DESCRIPTION

In a preferred embodiment, the nature of this product is as a plumbing fixture primarily useful for washing the body of humans.

FIG. 1 is a right, top, front perspective view of a tub for bathing embodying our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a cross-sectional view thereof taken along line 8—8 of FIG. 2; and,

FIG. 9 is a cross-sectional view thereof taken along line 9—9 of FIG. 2.

The broken line representations of holes in FIGS. 1—9 are for the purpose of illustration only, and form no part of the claimed design.
